COIN DISPLAY DEVICE

BACKGROUND OF THE INVENTION

It is necessary for coin collectors to examine coins for certain detail in order to make a determination as to the worth of the coin. A coin collector must examine many coins before he finds one having value to him as a collector. Heretofore, coin collectors have spread a plurality of coins out on a flat surface and have then moved a magnifying glass backwards and forwards across the surface to inspect each coin individually. The coins have then been turned over to expose their opposite sides and the process repeated. This has been a time consuming process and has limited the number of coins which a collector could examine in a search for a coin having particular markings.

SUMMARY OF THE INVENTION

The present invention relates to a display device which will facilitate the individual removal of a coin from a magazine to bring it to a location for optical inspection following which it is discharged to a magazine for holding the rejects. The device provides optimum optical conditions for observation of the coins. The device includes jaws having a configuration permitting their entry into a magazine, and the automatic removal of one coin from the magazine. The jaws are supported on a reciprocable spindle, and the device further includes mechanism which automatically opens the jaws at a proper position for discharging the coins into a reject magazine. Guide means are preferably also provided which assures proper rotational alignment of the jaws both when removing a coin from the supply magazine, and when discharging the coin into the reject magazine.

An object of the invention is the provision of a new and improved display device for coins and the like which will properly align and permit rotation of the coin beneath an optical viewer for examination purposes, and which will facilitate rapid movement of individual coins from a supply magazine to the location beneath the optical viewer, as well as the quick and orderly discharge of rejected coins into a discharge magazine.

A further object of the invention is the provision of a new and improved device of the above described type having guide means for a jaw support spindle which necessitates rotation of the jaws when moved axially in one direction past the display position, but which will permit axial movement without rotation in the display position when moved in the opposite axial direction.

Further objects and advantages of the invention will become apparent to those skilled in the art to which it relates from the following description of the preferred embodiment described with reference to the accompanying drawings forming a part of this specification.

DESCRIPTION OF THE DRAWINGS

FIG. 1 is a front elevational view of the preferred embodiment of the invention;

FIG. 2 is an end elevational view of the embodiment shown in FIG. 1;

FIG. 3 is an enlarged sectional view taken approximately on the line 3-3 of FIG. 1;

FIG. 4 is an enlarged fragmentary view taken approximately on the line 4-4 of FIG. 2 and showing another embodiment of the invention; and

FIG. 5 is an enlarged sectional view taken approximately on the line 5-5 of FIG. 4.

DESCRIPTION OF THE PREFERRED EMBODIMENT

The embodiment shown in the drawings generally comprises a pedestal 10 which supports a tubular coin magazine 12 at its upper end. The coin magazine 12 is closed off at its lower end by a magazine base 14 which fits into a suitable recess 16 in the upper end of the pedestal. The tubular coin

magazine 12 has a slot 18 therein in its sidewalls immediately above the magazine base 14. The slot 18 is only slightly wider than the thickness of the coin which the magazine is intended to hold, and the slot extends around the periphery of the magazine for approximately 220°, so that more than one-half of a coin positioned at the bottom of the magazine will be exposed to the outside of the magazine for reasons which will later be apparent.

Coins positioned in the magazine 12 opposite the slot 18 are adapted to be removed by a pair of thin jaws 20 that are formed by cooperating end portions of crossing levers indicated generally at 22 and which are pinned at their point of crossing and to the end of a spindle 26 by a pin 24. In the embodiment shown, the end of the spindle 26 is provided with a U-shaped bracket 28 whose legs 30 extend axially over opposite sides of the levers and through which the pin 24 extends. The spindle 26 is supported from a portion 32 of the pedestal by a brass bushing 30 that is so positioned as to guide the spindle for axial movement directly toward and away from the slot 18. In the embodiment shown, the bushing 30 projects through a suitable opening 34 in the pedestal portion 32 and is clamped in place by means of a setscrew 36.

The ends of the jaws 20 are provided with V-shaped projections 38 for the purpose of camming over the major diameter of a coin positioned in the slot 18. The end surface 40 of the V is tapered so as to slide up over the side edge of a coin until the apex passes the major diameter of the coin, and thereafter the taper provides clearance with the end surface of the slot 18. The inner surface 42 of the V is shaped to engage the edge of the coin on the opposite side of its major diameter from the spindle 26, while another abutment 44 engages another edge surface of the coin on the spindle side of the major diameter. The coin is thereby held between the inner surface 42 and abutments 44 of the opposing jaws.

The apexes of the V-shaped projections 38 are normally held on opposite sides of the axis of the spindle 26 at points equidistant therefrom by a pair of torque springs 46. Each torque spring 46 has a pair of laterally extending legs 48, one end of which is suitably fixed to the U-shaped bracket 28 while its other leg is suitably fixed to a respective one of the crossing levers 22. In the normal condition of the torque springs 46, the apexes of the V-shaped projections 38 are spaced apart by a distance less than the diameter of the smallest coin which the jaws are intended to grasp.

The jaws 20 are adapted to, when in a horizontal position, be moved axially by the spindle 26 into the slot 18 to grasp a coin as above described. Thereafter the coin is withdrawn by the jaws as the spindle 26 is withdrawn to move a coin to a display position shown generally in FIG. 1 of the drawings. In the display position shown in the drawings, the spindle 26 can be revolved to support either side of the coin at any angle desired by the viewer. In the embodiment shown, a magnifying glass 50 is held by the pedestal in position to view a coin when in the viewing position shown in the drawings. In the preferred embodiment shown, the magnifying glass 50 is supported by an L-shaped bracket 52, the horizontal leg of which supports the magnifying glass, and the opposite leg of which has an opening through which the brass bushing 30 extends. The magnifying glass can be moved radially about the bushing 30 without changing the distance therefrom and can be clamped in any desired radial position by means of a setscrew 54.

The device shown is adapted to automatically release a coin held by the jaws 20 when the spindle 26 is withdrawn outwardly from the viewing position shown. The release is accomplished by a tapered abutment surface 56 that is supported at a location to engage the jaw spreading ends 58 of the crossing levers 22 to bias the levers 22 apart as the spindle 26 is pulled away from the coin magazine 12 from the viewing position of the jaws. In the embodiment shown in the drawings, the jaw-spreading ends 58 of the levers 22 are provided with rollers 60, and the abutment surface 56 is formed by means of a flange on the end of the brass bushing 30. Also in the embodiment shown, a tubular coin-receiving magazine 62 is sup-

ported by the pedestal 10 with the open end of the magazine directly below the point where the jaws 20 release the coins. The coin release position of the jaws will be hereafter called the discharge location. The receiving magazine 22 may be identically shaped with the supply magazine 12 and may be supported from the pedestal by means of a recess identically shaped with the recess 16. The preferred embodiment is also provided with a lamp 64 that is housed within the L-shaped bracket 52 directly below its horizontal leg so that the bracket 52 will shield the light of the lamp from the eyes of the viewer. The lamp may be supplied from any source of electricity, and is preferably supplied with electricity by an electrical cord adapted to be connected to a 110 volt alternating current socket.

The device so far described is used by grasping the end of the spindle between the index finger and the thumb and rotating the spindle until the jaws 20 are horizontal. Thereafter the spindle is slid inwardly to move the jaws 20 into the slot 18 until the apex of the V-shaped projections slide over the side edges of a coin to grasp the coin between their rear surfaces 42 and the abutments 44. Thereafter, the spindle 26 is withdrawn to the display position shown in the drawings where the spindle is then rotated 180° to bring the opposite side of the coin in view beneath the magnifying glass. Thereafter, the operator pulls the spindle outwardly to cause the rollers 60 to move up the abutment surface 56 to spread the jaws 20 apart. The receiving magazine 62 is directly below the discharge position of the jaws and the coin then falls into the receiving magazine. The spindle 26 is then slid forwardly again to enter the slot 18 and repeat the operation.

Referring to FIG. 3, the spindle 26 is provided with a guide pin 70 and the bushing 30 is provided with a guide groove having a first longitudinally extending portion 72. The first portion 72 of the guide groove extends from a position occupied by the pin 70 when the jaws 20 are in the slot 18 to a position which it occupies when the jaws are in the display position shown in FIG. 1.

In the embodiment shown in FIGS. 1 through 3, the guide groove has a second portion 74 which extends radially for 180° to permit the pin 70 and spindle 26 to rotate 180° while the jaws are in the display position. The guide groove includes a third portion 76 which is located at the opposite end of the radial portion 74. The third portion 76 extends longitudinally from the radial portion 74 in the direction away from the magazine 12. The radial portion 74 is located in the end of the bushing 30, and the third portion 76 is located in a cap 78 that is threaded onto the end of the bushing 30. The third groove portion 76 receives the guide pin 70 when the jaws are moved from their display position outwardly to the coin release position. The rollers 60 engage the abutment face 56 during the time that the pin 70 moves longitudinally in the groove portion 76. The process is repeated by sliding the spindle inwardly, rotating it 180° in the viewing position and then sliding the spindle inwardly to pick up another coin.

In the embodiment shown in FIGS. 4 and 5, the spindle can be slid longitudinally from the release position to the pickup position without rotating the spindle in the viewing position. Those portions of the embodiment shown in FIGS. 4 and 5 which correspond to similar portions of the embodiment shown in FIGS. 1 through 3 are designated by a like reference numeral characterized further in that a prime mark is affixed thereto. This is accomplished in the embodiment shown in the drawings by providing a counterbore 80 in the end of the bushing 30' which provides a radial second portion 74' of the groove which extends for 360° around the spindle. An annular disc 82 is clamped between the end of the bushing 30' and the cap 78' to form the end wall of the counterbore 80. The disc 82 is serrated to provide a spring portion 84 which is hinged at its bottom to the disc 82 and which extends clockwise about the spindle 26'. The spring portion 84 extends diagonally forward across the radial groove 74' so as to cam the pin 70' counterclockwise to bring the top side of a coin parallel with the magnifying glass when the spindle is withdrawn from the supply magazine. Thereafter, the spindle 26' can be rotated

either for another 180° in the same direction to expose the bottom of the coin or can be rotated clockwise while pulling axially on the spindle 26 to bend the spring 84 out of the way and allow the pin to proceed clockwise past the spring until

5 the bottom side of the coin is parallel with the magnifying glass. Thereafter, the spindle is rotated counterclockwise to bring the pin downwardly upon the top surface of the spring 84 to cam the pin 70' into a longitudinally extending slot 76' in the cap 78'. The rollers 60' engage the abutment face 56' 10 during the time that the pin 70' moves longitudinally in the slot 76' to release a coin held by the jaws into the receiving magazine 62'. The process is repeated by simply sliding the spindle 26' forwardly without rotation. The pin 70' then bends the spring 84 downwardly so that the pin 70' passes directly 15 into the groove section 72' which holds the jaws in proper alignment for insertion into the slot 18'. The bottom of the groove 72' is notched out as at 86 to receive the spring 84 as the pin 70' is slid over the top of the spring 84 into the groove section 72'.

20 While the invention has been described in considerable detail, I do not wish to be limited to the particular embodiment shown and described, and it is my intention to cover hereby all novel adaptations, modifications, and arrangements 25 thereof which come within the practice of those skilled in the art to which the invention relates.

I claim:

30 1. A coin display device comprising: a pedestal, a spindle, a pair of crossing jaws pivoted at their crossover point to said spindle, first means mounting said spindle on said pedestal for longitudinal sliding movement forwardly and rearwardly of said means and for rotation of said spindle relative to said means, second means mounting a magazine on said pedestal in line with said spindle forwardly of said first means, said magazine having a jaw-receiving opening facing said first means, said jaws having two pairs of inner facing abutments, the abutments of each pair being opposite each other and the pairs of abutments being spaced longitudinally relative to said spindle, spring means biasing said jaws toward each other, and 35 a tapered abutment adapted to be abutted by portions of said jaws located rearwardly of said crossover point when said abutments are outside of said magazine, whereby said jaws are opened when said spindle is moved rearwardly to bring said portions of the jaws located rearwardly of said crossover point 40 against the tapered abutment.

45 2. The coin display device of claim 1 including: guide means for controlling rotational and sliding movement of said spindle, said guide means having a portion which allows at least approximately 180° of rotation of the spindle when said jaws 50 are in a display location intermediate said magazine and said discharge location, and having a portion which restrains spindle rotation to guide said jaws into the jaw-receiving opening of said magazine.

55 3. The coin display device of claim 2 wherein said guide means comprises a laterally projecting pin on said spindle which is received in a guide slot supported by said base, said guide slot having a first portion extending parallel to the axis of said spindle between its location where said jaws enter said 60 slot and where said jaws approach said display location, said guide slot having a second portion extending radially around said spindle at the location of said pin when said jaws are in said display location, and said guide slot having a third portion extending parallel to the axis of said spindle in the location 65 traversed by said pin when said jaws are moved from said display location to said discharge location.

70 4. The coin display device of claim 3 wherein said guide means includes a guide spring located in said second portion of said guide slot on its wall opposite said first portion of said guide slot, said guide spring having a normal position extending-diagonally across said second portion to deflect said pin radially and prevent axial pin passage from said first portion of said guide slot directly into said third portion of said guide slot, said guide slot having clearance into which said guide spring moves clear of said first portion when said pin is moved axially from said third portion directly to said second portion.
